[57] **CLAIM**

The ornamental design for a table-top air filtering unit to reduce dust and fumes for use in a manicurist environment, as shown and described.

DESCRIPTION

FIG. 1 is a perspective view showing the top, front and left sides of a tabletop air filtering unit to reduce dust and fumes for use in a manicurist environment design;

FIG. 2 is an enlarged top plan view thereof;

FIG. 3 is an enlarged left side elevational view thereof;

FIG. 4 is an enlarged front elevational view thereof, the rear elevation being substantially a mirror image of the front side as shown;

FIG. 5 is an enlarged right side elevational view thereof; and,

FIG. 6 is an enlarged bottom plan view thereof.

The dot pattern is understood to be repeated throughout the top surface in FIGS. 1 and 2, and is only shown partially for ease of illustration.
